UNITED STATES PATENT OFFICE.

JAMES MORLEY, OF MALDEN, MASSACHUSETTS.

DESIGN FOR A PRINTING TYPE OR PLATE.

No. 37,764.

Specification for Design.

Patented Dec. 26, 1905.

Application filed November 18, 1905. Serial No. 288,079. Term of patent 7 years.

To all whom it may concern:

Be it known that I, JAMES MORLEY, of Malden, in the county of Middlesex and State of Massachusetts, have invented a new, original, and ornamental Design for a Printing Type or Plate, of which the following is a specification, reference being had to the accompanying drawing, forming part thereof.

The figure is a plan view of the printing type or plate, showing my design.

I claim—

The ornamental design for a printing type or plate, as shown.

JAMES MORLEY.

Witnesses:

MARY E. MORLEY,
ARTHUR P. MORLEY.
